Patented Apr. 25, 1899.

E. E. CROOK.

HYDROCARBON BURNER.

(Application filed May 31, 1898.)

(No Model.)

UNITED STATES PATENT OFFICE.

EDWIN E. CROOK, OF INDIANAPOLIS, INDIANA.

HYDROCARBON-BURNER.

SPECIFICATION forming part of Letters Patent No. 623,518, dated April 25, 1899.

Application filed May 31, 1898. Serial No. 682,150. (No model.)

To all whom it may concern:

Be it known that I, EDWIN E. CROOK, a citizen of the United States, residing at Indianapolis, in the county of Marion and State 5 of Indiana, have invented certain new and useful Improvements in Hydrocarbon-Burners, of which the following is a specification.

The common practice in starting hydrocarbon-burners has been to heat the generator 10 by burning oil in an open pan under it, and while this is a quick method of getting the fire started it is quite objectionable on account of the disagreeable odor of the oil which unavoidably escapes, and because of the excessive production of soot, which collects on 15 the burner and inside of the stove, making all parts reached by it smutty and dirty.

One object of this invention is to provide means whereby the initial heating of the generator can be accomplished without odor and smoke in perhaps a little longer time than by the open-pan method, but also in which the open-pan method can be quickly employed whenever quicker results are essential,

25 Another object is to distribute the oil uniformly over a larger area of the pan than heretofore, and the object also is to facilitate the transmission of heat from the walls to the oil on the inside of the generator.

30 The object of the invention also is to provide means whereby the flame and heat from the burning vapors can be controlled and directed at will against the stove-top or down toward the oven, as the circumstances may 35 require.

I accomplish the objects of the invention by the mechanism illustrated in the accompanying drawings, in which—

Figure 1 is a detail in vertical section of 40 my improved burner, showing the pipe connections for the supply of oil and the transfer of the vapors. Fig. 2 is a detail in side elevation, partially in section, of the upper half of the generator and superimposed parts. Fig. 3 45 is a horizontal section of the generator on the dotted line 3 3 looking in the direction of the arrows, and Fig. 4 is a like view of the oil-pan on the dotted line 4 4. Fig. 5 is a view, on a larger scale, of the oil-pan and initial 50 heating apparatus. Fig. 6 is a side elevation of the hood which covers the lamp under the generator, and Fig. 7 is a section of same on

the dotted line 7 7 of Fig. 6 looking in the direction of the arrows.

A is the tank which contains the oil to be 55 used, and which oil will preferably be one of the residuals of petroleum after the gummy properties and most valuable commercial ingredients of the crude oil have been removed.

B is the retort or generator, which is oval 60 or circular in outline and is flattened at the sides and in many respects is similar to other generators heretofore used for the same purpose. It has the central walled opening B' and is supplied with oil from the tank A through 65 the pipe A'. The latter has the cock a, by means of which the oil is turned on or off. The oil is vaporized in the generator B, and the vapors are carried down through the pipe B² and are discharged at the lower end of the 70 opening B', where they mix with air and pass up through the opening into the spreader C. The spreader C is a removable conical cap with a vertical downwardly-projected annular flange C', which is provided with the slots 75 or kerfs c, through which the mixed vapor or air introduced into the concavity of the spreader issues. The ignition of the gases takes place outside of the kerfs, and the heat generated raises the temperature of the generator-walls, thereby causing the oil contained 80 in the generator to become heated to volatilization. This is encouraged by the formation of the concentric walls b, which conduct the heat down into the oil, and by the radial 85 flanges b', integral with the top, bottom, and sides of the generating-chamber. The latter by being located immediately under the flame of the ignited gas assist very materially in conducting the heat into the oil. Radial 90 flanges b² around the walls of the central opening B' are specially advantageous in the initial heating of the generator, as will herein-after more clearly appear.

In cooking on top of the stove it is desirable 95 that the gas-flame and heat be directed against the lids of the stove, and for that reason the annular flange D', a suitable distance from the kerfed cap, is provided. For baking, roasting, and such operations as require 100 the use of the oven it is desirable that the heat and flame be directed downward in the direction of the oven, and to provide for this I make a depression in the outer margin

of the generator-top to receive an annular plate D, and I provide suitable means for elevating this plate until its under side is above the kerf-terminals of the spreader, thereby permitting and forcing the flame to pass between the plate and the top of the generator. The contour of the under side of the plate D is such as to direct the flame in a downward direction. In the drawings I have shown the cams or eccentrics d for giving the proper elevation to the plate D; but other means can be adopted without departing from the spirit of this invention, the essential feature of which is the adjustable plate itself and not the means for securing that adjustment.

I will now describe the means by which the initial volatilization of the oil is accomplished in starting the action of the burner.

E is the oil-pan, which has a central opening surrounded by an upwardly-projected wall or flue E', at the base of which is an outside annular concavity or depression e of considerable depth to receive and hold a supply of oil, which is conveyed to it through the pipe A², which is a branch from the pipe A', as shown in Fig. 1 of the drawings. It is provided with the cock a^2 , by which it is opened or closed at the will of the operator. Surrounding the flue E' and resting on and bolted to the bottom of the pan is a plate F, having a central opening of course, and surrounding this opening is the vertical wall or flue F', the diameter of which is greater than the outside diameter of the flue E' to a degree sufficient to provide space for a wick G, which is placed between the two flues. This wick will be of non-combustible material, preferably such as asbestos, and its lower end will rest in the oil-depression e , from which by capillary action the oil will be diffused throughout the wick and will be ignited at the top of the latter. The wick will be fastened to a metal band G'. The two ends of an adjusting-rod g will be fastened to diametrically opposite sides of the band, and the middle portion of the rod will be bent over the flue E' and carried down inside of the flue and to an accessible point below it, where it can be manipulated to raise and lower the wick. The plate F will have under-side radial grooves j' , forming channels through which an excess of oil discharged into the depression e will overflow into the pan. The plate also has outside marginal lugs projected upwardly or a continuous marginal flange, as shown at f in the drawings, to which the base of a truncated conical hood H is secured by bolts, rivets, or otherwise. This hood is bolted in like manner to lugs depending from the under side of the generator. The front of the hood will be cut away to permit access to the wick when it is desired to light the oil on the latter, and this opening is closed by a sliding door H'. An air-space h between the hood and the generator will be provided, and the sliding door may

be made to form a closure for this opening also, if desired.

When the oil on the wick is ignited, the flame will have center draft as well as outside-air supply, and the hood and walled opening through the generator will act as a flue to insure complete combustion of the carbon in the oil and prevent the formation of soot. The escape into the room of the disagreeable oily smell will also be prevented.

Experience will indicate the proper amount of oil to be admitted into the cavity e , and when the oil is all consumed the fire on the wick will go out.

Should it be desired to secure quick action in starting the generation of gas in the generator, a supply of oil may be admitted through the pipe A² to flood the bottom of the pan E, and the oil will then be ignited in the pan in the usual way. To insure a more even diffusion of the oil in the pan, I prefer to slope the bottom of the latter upwardly toward the center and provide a series of annular ribs E², which will retain a portion of the oil and allow only the overflow to pass down to the next rib, and so on. The walls b and flanges b' carry the heat up into the oil from the bottom of the generator in the same manner as the heat is carried down from the top after the burner is working normally, and the flanges b^2 around the center opening conduct the heat into the oil from the center tube. Transverse openings b^3 permit free circulation of oil around the base of the vapor tube.

Having thus fully described my invention, what I claim as new, and wish to secure by Letters Patent of the United States, is—

1. The combination, with a retort having a central vapor-tube, a kerfed spreader or cap resting on the retort over the tube and a vertically-adjustable plate to throw the flame from the spreader up or down, substantially as described and for the purposes specified.

2. The combination, with a retort having a central vapor-tube, a spreader resting on the retort over the tube and adjustable means connected with the burner for throwing the flame of the burner up or down for the purposes specified.

3. The combination, with a retort having a central vapor-tube, a kerfed spreader or cap resting on the retort over the tube and a vertically-adjustable plate resting on the retort outside of the spreader below the kerfs and having a flange to direct the heat and flame in an upward direction, said plate having an outwardly and downwardly shaped under side and means for elevating the plate to a position above the kerfs of the spreaders and sustaining it in its elevated position substantially as described and for the purposes specified.

4. The combination, with the retort having a central vapor-tube with flanges on the inside of the retort radiating from the tube

and other radial flanges around the inside of the retort integral with its marginal wall but not connected with the central tube or its flanges, and a kerfed spreader resting on the 5 retort over said central tube.

5. The combination, with the retort having a central vapor-tube with flanges on the inside of the retort radiating from the tube, with transverse openings through the lower 10 inner corners of the flanges, substantially as shown, and a kerfed spreader resting on the retort over said tube.

6. In a hydrocarbon-burner, a generator having a vertical vapor-tube, a spreader resting on the generator over the vapor-tube, an 15

auxiliary burner below the generator under the tube having an oil-receptacle at its base and having overflows, means for supplying oil to the receptacle, a pan surrounding the auxiliary burner into which the overflow from 20 the receptacle is deposited and a hood surrounding the auxiliary burner.

In witness whereof I have hereunto set my hand and seal, at Indianapolis, Indiana, this 29th day of April, A. D. 1898.

EDWIN E. CROOK. [L. S.]
